UNITED STATES PATENT OFFICE

HOMER P. CHANDLER, OF MANSFIELD, OHIO, ASSIGNOR TO THE OHIO BRASS COMPANY,
OF MANSFIELD, OHIO, A CORPORATION OF NEW JERSEY

ELECTRIC SWITCH

Application filed October 22, 1926. Serial No. 143,500.

My invention relates to electric switches and has particular reference to a switch adapted for use in mines or other places where gas of an explosive character is present.

3 The object of my invention is to provide a device which is gas or flame proof and by which the electric circuits can be made or broken without danger of igniting the gases.

10 Another object of my invention is to provide a device in which contacts can be made and broken in connection with the device, but outside thereof, and whereby sparking or arcing is prevented and this is brought about by arranging the contacts to and from the device so that they may be made or broken only when the switch is in its open position.

15 Another object of my invention is to provide a device in which the cover cannot be removed or replaced with the switching mechanism in a closed or partially closed relation to the terminals or a device in which the switch is inoperative until the cover has been entirely replaced.

20 A further object of my invention is to provide a quick break action to the switch in breaking the circuits.

25 Another object of my invention is to provide a switch in which there is a plurality of breaks so that the arcing upon opening a circuit is divided between two or more breaks.

Another object of my invention is to provide a switch of the quick break rotatable type in which the rotating portion and its mechanism is removable with the cover of the device.

30 Another object of my invention is to provide a switch in which the circuit or circuits controlled by the switch are protected by fuses within the switch.

35 A further object is to arrange the device so that the fuses cannot be inserted or removed while the switch is closed or the terminals to which the fuses are attached are alive.

40 Another object of my invention is to provide means for locking the cover and casing against separation by unauthorized persons.

45 A still further object of my invention is to provide means to relieve the strain upon the

detachable cables which make temporary connection with the device.

Other objects will be apparent to those skilled in the art as I proceed with the description of my invention.

55 My invention resides in the new and novel construction, combination and relation of the various parts herein described and shown in the accompanying drawings.

In the drawings:

Fig. 1 is a top view of my invention showing the exterior view of the switch when in a closed position with auxiliary cables secured thereto and which lead to the apparatus controlled by the switch.

60 Fig. 2 is a side view of Fig. 1.

Fig. 3 is a sectional view of my switch on the line 3—3 of Fig. 1.

Fig. 4 is a sectional view of my switch on the line 4—4 of Fig. 1.

Fig. 5 is a sectional view on the line 5—5 of Fig. 1.

Fig. 6 is a sectional view of the rotatable member taken on the line 6—6 of Fig. 5.

Fig. 7 is a sectional view on the line 7—7 of Figs. 3 and 5.

Fig. 8 is a sectional view on the line 8—8 of Figs. 3 and 5.

Fig. 9 is a developed view of the inner circular insulated lining of the casing to show 80 the slots and recesses as later described, and also showing the relation of the fixed contact members to the various features of this lining. It is sectioned on the line X—Figs. 10 and 11.

85 Fig. 10 is a sectional view of the more important details of my switch taken on the line 10—10 of Fig. 3 and Fig. 9.

Fig. 11 is a sectional view of the more important features of my invention taken on 90 the line 11—11 of Fig. 4 and Fig. 9.

Fig. 12 is an end view of Fig. 9.

In the preferred embodiment of my invention I employ a casing 1, preferably made of metal, and threadably secured thereto is a 95 cover 2. The threads are of sufficient length and fit sufficiently close so that under normal conditions gas cannot enter the casing and any flame or arc produced within the casing can have no effect upon the exterior gases.

There are four openings shown in the upright side of the casing although the number of such openings may be varied to meet the requirements. In the present case the four openings are intended to take care of the two sides of a circuit. In the bottom of the casing is a disc of insulating material 3 which is not only an electrical insulator, but is non-inflammable and also water proof, such as fiber, asbestos impregnated with a water proofing compound or bakelite composition.

Snugly engaging the interior side wall of the casing is an insulating member 4 which can be made in one or more pieces and is shown in a developed view in Fig. 9. This insulating member 4 has four openings in the side to correspond and register with the four openings through the side wall of the casing previously mentioned.

Passing through the openings in the side wall of the casing and insulating member 4 are terminal members 5 each surrounded by an insulating bushing 6 which electrically separates the terminal from the metallic casing 1. The bushings 6 and the terminal members 5 are provided with engaging shoulders and the bushings 6 are each provided with a shoulder engaging the casing 1, while the inner end of the terminal member 5 is provided with a thread engaged by the combined nut 7 and spring clips 8 (see Fig. 9), which when drawn up tight draws the shoulders on the parts referred to into close engagement with each other and securely locks the terminals 5 and the bushings 6 in position, and with properly fitting parts and the use of cement or gaskets, if necessary, the side openings through the wall of the casing are rendered gas tight. The construction of the bushings and terminals just referred to also locks the insulating member 4 in position with respect to the casing.

The terminal members are positioned ninety degrees apart and each terminal is provided with a socket and two of the adjacent terminals are provided with cables 9 and 10 respectively and which are secured permanently, one in each socket, and these cables are, as a rule, connected permanently to the source of power.

The casing is provided with four lugs 11 for mounting the switch in permanent position. One of the lugs is provided with a pair of chains 12 to the free end of which is connected a snap hook 13 adapted to snap on and off the cable clamps 14 when desired.

The cover and casing are provided with lugs 15 which have registering holes when the cover is in its final closed position and a padlock 16 can be inserted through the registering holes and the casing locked against opening by an unauthorized person if desired.

The terminals opposite those to which the cables 9 and 10 are permanently secured are

arranged to have connected thereto a plug connection 17 and which connection can be applied to or removed from the terminal under proper conditions. Each plug connection 17 has an inner terminal 18 provided with a socket at one end to receive the cable 19 or 20 in fixed relation. The terminal 18 is surrounded by the insulating sleeve 21 which is threadably secured to the terminal and the insulating collar 22, which in turn is secured to the sleeve 21. The sleeve 21 can extend away from the bushing 22 any distance desired, although six or eight inches is sufficient in order to provide a grip for the hand in applying or removing the plug contact. The parts 21 and 22 can, if desired, be made of one piece as by molding or cutting from solid material.

It will be noted that when the plug contact 17 is in position that there are no exposed parts of the live members and when the plug contact 17 is removed the terminals 5 are well protected from contact therewith. The insulating bushing 6 can be molded on to the terminal 5, if desired, which is common practice in this class of work.

The interior surface of the cover 2 is provided with an insulated lining 23 similar to that of 3.

The cover 2 is provided with an upwardly projecting boss 24 having a passage therethrough and in which is mounted a shaft 25 having the collar 26 at the inner end and provided with the oppositely projecting arms 27. Mounted upon the shaft 25 is a collar 28 from which project the arms 29 at right angles to each other with an intervening brace 30. The collar 28 is secured to the shaft 25 by means of the set screws 31 and provides a means of maintaining the collar 26 in close contact with the inner face of the cover 2.

Also mounted upon the shaft 25 is another collar 32 which is provided with a boss 33 which is threadably secured to the handle 34. The collar 32 has a limited amount of rotation relative to the shaft 25. The upper end of the shaft 25 is provided with the upwardly extending and spaced lugs 35 as shown in Fig. 8, while the upper end of the collar 32 to which the handle is attached is provided with the oppositely disposed and inwardly projecting lugs 36 adapted to engage and cooperate with the lugs 35 and permitting an amount of relative rotation equal to the space 37 as shown in Fig. 8.

It will be evident that when the collar 32 is rotated by means of the handle 34 the lugs 36 are arranged to engage with the lugs 35 on the shaft 25 and force a movement of the shaft 25. The shaft 25 is hollow throughout its length and extending upwardly within the shaft 25 from the lower end is a stud 38 provided at its upper end with a slot to receive the end 39 of the spring 40. This arrangement anchors the lower end of the spring 40 to the shaft 25 and prevents

relative movement of the lower end of the spring and the shaft 25. Extending inwardly from the upper end of the shaft 25 is a plug 41 having a flange 42 at its upper end and a slot in its lower end to receive the upper end 43 of the spring 40 and thereby hold the end 43 of the spring in fixed relation to the plug 41 and the plug 41 in turn is secured to the collar 32 to which the handle is attached by means of the screws 44.

From this it will be seen that the lower end of the spring 40 is fixedly secured to the shaft 25 and the upper end of the spring 40 is fixedly secured to the collar 32 to which the handle 34 is attached, and that there is a permitted relative movement of the handle with respect to the shaft 25, and by properly tensioning the spring 40 by adjustment of the plug 41 there will be a normal tendency of the handle and shaft to rotate relative to each other through the action of the spring thereby giving to the shaft 25 a quick movement through the tension of the spring when the handle is moved in a direction tending to open the switch, and a preliminary movement of the handle in a direction to open the switch will tend to increase the tension in the spring 40 and the engagement of the lugs 36 with the lugs 35 will force the switch from its closed position and as soon as released the spring tension will throw the switch quickly out of engagement with its contacts thus providing a quick break switch.

To the upper end of the plug 41 is secured a cap 45 by means of the bolts 46 which engage with the lugs 35 as shown in Fig. 8, and pass through slots 47 provided in the flange 42 and above the lugs 35. The purpose of the cap 45 is to seal the adjustment of the spring tension and against easy tampering therewith, and the loosening of the screws 46 can be prevented by drilling a small hole through the head of each and passing a small wire 48 therethrough and twisting and soldering the same in fixed position.

To the lower face of the arms 27 is secured a circular disc of insulating material 49 and two spaced insulating members 50 by means of the screws 51'. To the lower face of the insulating plugs 50 is secured the insulated disc 51 by means of the screws 52 (see Fig. 6).

Mounted upon the upper face of the disc 51 at diametrically opposite points are the terminal members 53, the through bolts 54 securing the terminals 53 in position, and each terminal 53 is provided with a blade 55 to engage with the spring contacts 8, shown in Fig. 3, when the switch is in closed position. Connecting the terminals 53 is an enclosed fuse C. From this it will be seen that when the switch is closed, as shown in Fig. 3, the oppositely disposed terminals 5 will be electrically connected.

Mounted upon the under side of the insulating disc 51 and rotated ninety degrees

from the fusible connection on the upper side of the disc 51 is a fusible element D which has terminals 56 similar to the terminals 53 and provided with the blades 57 which engage with the spring clips 8 shown in Fig. 4, and connect the terminals 5, shown in Fig. 4, when the switch is in a closed position.

From this description it will be seen that when the switch is closed the diametrically opposite terminals projecting through the casing are electrically connected by means of a fused connection, and from the previous description it will be seen that the switch is closed when the handle 34 is rotated in one direction, as for instance, in a clockwise direction, and the switch is opened by a quick break movement when the handle is moved in an anti-clockwise direction.

The discs 58 are of insulating material and are for the purpose of covering the screw heads used in securing the terminals 53 and 56 to the disc 51 thereby adding extra protection against leakage and short circuits within the switch.

The insulating member 4 is arranged with vertical and horizontal slots by means of which the opening and closing of the casing is controlled so that the same cannot take place only when the switch mechanism is in closed position with respect to the terminals, and this is brought about by the cooperation of the vertical and horizontal slots with the switch blades 55 and 57 and also the member 51 with the terminal parts 7-8.

In Fig. 9 is shown the inner face of the insulating member 4 in a developed form as though the insulating member was removed from its casing and split along the lower edge or line X (Fig. 10) and unrolled in the direction of the arrows A and B.

The various terminals projecting through the casing are also shown in position in Fig. 9 with relation to the slots. When the switch is in a closed position the terminals shown on the lines Y and Y' are connected as by the fused connection C and the terminals shown on the lines X and X' will be connected by the fused connection D. While in this position it will be apparent that the cover cannot be unscrewed because the rotatable switch, which is secured to the cover, is interlocked with the permanently secured spring clips 8, in fact, as there is no vertical lost motion between the cover 2 and the stem 25 the amount of rotation which might be imparted to the cover 2 is found not to exceed a one-half to one turn of the cover. When opening the switch, I have provided for a revolution of the rotatable switch members of approximately 135 degrees, which will mean that in the open position the connection C would coincide with the lines Y^a and Y^b, and in this position the cover can be unscrewed and the switching mechanism can be removed through the vertical slots shown in the de-

veloped Fig. 9 and corresponding with the lines X^a , X^b , Y^a and Y^b . When the switch is in the fully opened position, as just described, the cover can be rotated and as the cover rotates it will naturally rise and move along the axis of rotation and with it the rotatable switching mechanism, and the blades being positioned in the slots referred to, there is no obstruction to their rising with the cover and when the cover has been fully rotated out of threadable engagement with the casing the cover and rotatable switching mechanism is removed as a single unit, leaving the interior of the casing substantially free of all parts, excepting the insulating member 4 and the through terminals.

Should an attempt be made to remove the cover while the switch is in a partially open position, it will be found that it is impossible to do so for the reason that the blades 55 will be in engagement with the upper horizontal slots coinciding with the line 10-10 of Fig. 9 in the insulating member 4, and the blades 57 will be in engagement with the lower horizontal slots coinciding with the line 11-11 of Fig. 9, or it will be found that the disc 51, which is positioned below the upper spring clips 8, will engage with the upper spring clips 8 and prevent the rotatable switch mechanism and cover from being moved upwardly.

In regard to the engagement of the disc 51 with the spring clips 8, it will be noted in Fig. 3 that the diameter of the member 51 is such that it will just pass through the circular opening formed by the flange 59 in the insulating member 4, and in order to bring it to its position below the upper spring clips 8, it is necessary to remove two opposite sides of the disc 51, as shown in Fig. 6. The short diameter of the member 51 is slightly less than the distance between the inner ends of the upper spring clips 8 and when the rotatable switch mechanism is in proper position to be removed the member 51 is in such position that its short diameter is positioned between the inner ends of the upper spring clips 8. In other positions of the rotatable switch mechanism the upper spring clips 8 will overhang the member 51, as shown in Fig. 3.

In replacing the rotatable switch member it is possible to start the insertion of the blades 57 in the slots corresponding to the lines X and X' , but as this is an improper assembly condition, the disc 51 will come in contact and rest upon the upper projecting spring clips 8 and prevent the insertion of the rotatable member within the casing.

I also provide means for preventing the closing of the switch until the cover has been entirely replaced to its final position or within a half or one turn thereof, and this is brought about by the fact that the lower blades 57, which enter the vertical slots indi-

cated as X^a and X^b in Fig. 9, cannot rotate or be rotated until the blades 57 have moved downwardly through the screwing on of the cover until they coincide with the horizontal slots 60 and the clearance between the thickness of the switch blade 57 and the width of the slot 60 is very small. If an attempt is made to rotate the switch mechanism while the blades 57 are in the vertical slots corresponding to X^a and X^b , they will merely engage the shoulders 61 until they coincide with the slots 60.

At the lower end of the vertical slots coinciding with the lines X^a and X^b are rubber bumpers 62 which are composed of soft yielding rubber and have their upper faces slightly inclined and tend to act as a cushioning in operating the switch from a closed position to an open position, and prevent the switch blades 57 from striking the side 63 of the slots X^a and X^b with any great appreciable force.

The arms 29 are bent downwardly at right angles and their lower ends are adapted to coincide with the two adjacent terminals through the side of the casing which are adapted to receive the removable plug contacts, and when the switch is in the closed position, if the plug contacts have not been properly positioned with respect to the terminals, then it will be impossible to connect plug contacts with the terminals as the lower end of the arms 29 will interfere and prevent such connection, and also if the plug contacts have been positioned with respect to the terminals and the switch is in a closed position, then the arms will be engaged by the flange 64 on the plug contacts and prevent the withdrawal of the plug contacts while the switch is closed.

Assuming that the switch has been properly installed and the connections 9 and 10 made to the source of power, then if it is desired to connect the leads 19 and 20 from some machine to be operated to the switch, it is only necessary to move the switch handle until the arms 29 are out of alignment with the contact terminals through the side of the switch and which insures the opening of the switch and permits the connection of the plug contacts with the side terminals and this having been done, the switch handle is then rotated in a clockwise direction which eventually closes the switch and connects the cables 19 and 20 to the cables 9 and 10 respectively.

To remove the connection between the cables 19 and 20 and the switch device, it is absolutely necessary to move the switch handle in an anti-clockwise direction, which first increases the tension on the spring 40 and then brings the lugs 35 into engagement with the lugs 36, and which in turn forces the movement of the rotating switch mechanism until the blades 55 and 57 dis-

engage with the spring clips 8 at which time the tension in the spring 40 causes a quick operation of the blades 55 and 57 with respect to the spring clips 8 and the switch is moved through practically one hundred thirty-five degrees to its open position. This throws the arms 29 out of alinement with the terminal lugs and it is then possible to remove the plug contacts.

While it is not absolutely necessary, still as a precaution against straining the connection between the cables 19 and 20 and the switch, I secure to each cable adjacent the plug contact the clamp 14 provided with means, such as an eye to which the snap hook 13 secured to the chain 12 can be attached thereby relieving the strain between the plug contact and the terminal of the switch.

If, for any reason, it is desired to examine the inside of the switch, it is then necessary to move the switch to its fully open position in which the blades 55 and 57 correspond with the vertical slots Y^a, Y^b, X^a and X^b, then to unlock and remove the padlock, if in position, and then to rotate the cover thereby moving the cover axially of the switch and with it the switching mechanism, and as soon as the cover has been rotated approximately a half to one turn it will be impossible to rotate the switch to a closed position thereby insuring the switch to remain open until after the cover has been removed.

When it is desired to re-assemble and close the switch, it is then necessary to position the blades 55 and 57 in proper relation with the vertical slots Y^a, Y^b, X^a and X^b and then to rotate the cover thereby moving it axially toward the casing, and it will be found impossible to rotate the switch mechanism until the cover has reached its final position within approximately one-half to one turn, thus insuring the casing being safely closed before it is possible to close the switch and possibly causing an arcing, which might be very disastrous were the switch used in a gaseous mine. Having the fuses enclosed within the gas tight casing is also a decided advantage in a gaseous mine as it protects the circuits and also avoids the flashing of the fuse igniting the gases, and combines in one device all the safety features required in a device of this character by the Bureau of Mines.

It is sometimes desirable to ground the casing and for that reason I provide the casing with a lug 65 having an opening to receive a cable 66, which is secured to the lug 65 by means of the screw 67. The cable 66 can be attached to a ground at some convenient point thereby grounding the casing.

There will be modifications which will suggest themselves to those skilled in the

art, but I wish to be limited only by my claims.

I claim:

1. A switch comprising in combination a casing and a removable cover, concealed means interlocked by rotation of one of the said parts relative to the other about a common axis to secure the parts together, insulated terminals passing through a wall of the casing, contact plugs to connect to the terminals, a switch mechanism to connect and disconnect the terminals, a swinging locking member to engage the plugs and prevent the disengagement of the plugs when the switch is closed and means operated simultaneously with the closing of the switch mechanism to prevent the removal of the cover while the switch is closed.

2. A switch comprising a casing and a removable cover secured together, insulated terminals passing through the casing, contact plugs to connect to the terminals, a switch mechanism to connect and disconnect the terminals, a locking member arranged to operate simultaneously with the switch mechanism and to lock the plugs against removal when the switch is closed, and means on the casing to be engaged by means on the switch mechanism and concealed means on the cover to engage concealed means on the casing to prevent the removal of the cover while the switch is closed.

3. A switch comprising a casing and a removable cover secured together, insulated and fixed terminals passing through the side walls of the casing, contact plugs to connect to the terminals, a switch mechanism provided with a blade secured to and removable with the cover relative to the fixed terminals and adapted to connect the terminals, means on the casing to be engaged by the switch blade to prevent removal of the cover while the switch is closed and means to prevent the removal of the plugs while the switch is closed.

4. A switch comprising a casing and a removable cover and securing means interlocked by rotation of one of the said parts relative to the other part, to secure the parts together, insulated terminals passing through the casing, contact plugs to connect other terminals, a switch mechanism secured to and removable with the cover to connect the terminals, means to prevent the removal of the plugs while the switch is closed, and means on the switch interlocked with means on the casing to prevent disengagement of the securing means to prevent removing the cover while the switch is closed.

5. A switch comprising a casing and a removable cover secured together by a screw threaded connection therebetween, insulated terminals secured to the casing, contact plugs to be connected to and disconnected from the terminals, a switch mechanism secured to and removable with the cover to connect the

- 5 terminals and means to prevent the connecting of the plugs or removal of the cover while the switch is closed or replacement of the cover while the switch is in a position to connect the terminals.

6 6. A switch comprising a casing and a removable cover secured together, insulated terminals mounted externally and internally of the casing, plugs arranged to be either connected to or disconnected from the terminals, a switch mechanism secured to and removable with the cover to either connect or disconnect the terminals, means to prevent either the connecting or disconnecting of the plugs 10 while the switch is closed and insulated means on the casing to interlock with means on the switch mechanism to prevent either the removal or replacing of the cover while the switch mechanism is in a closed position relative to the terminal members.

15 7. A switch comprising a casing and a removable cover, the cover and casing secured together by a concealed interlock between the cover and casing and operated by a relative 20 rotation of the cover and casing in either direction depending upon the cover being removed or replaced, insulated terminals passing through the casing and arranged for connections thereto exterior of the casing, a 25 switch mechanism secured to and removable with the cover, means exterior of the casing to operate the switch mechanism to its closed position and means interposed between the 30 switch and exterior operating means biased 35 to open the switch with a quick break and means to prevent either the removal or the replacement of the cover when the switch is in its closed position relative to the terminals.

40 8. A switch comprising a casing and a cover attachable and removable by rotation and means interlocking the two together to form a gas tight compartment, insulated terminals secured to the casing and having 45 means to connect thereto exterior of the casing, a rotatable switch mechanism secured to the cover and removable with the cover, means secured to the cover to operate the switch mechanism to its open or closed position and means to impart to the switch mechanism a quick motion when the switch mechanism is moved from its closed position.

50 9. A gas and flame proof switch comprising a casing, a rotatable removable cover interlocking gas proof connection between the cover and casing, a switch within the casing and operable by a means from without the casing, an insulated terminal having a gas 55 proof connection to the casing, a plug adapted to be connected to the terminal, means operable by the first said means to hold the plug in engagement with the terminal while the switch is in closed position and means to prevent the removal of either the plug or

55 the cover while the switch is in closed relation to the terminal.

60 10. A switch comprising a casing, a cover for the casing secured thereto by a screw-threaded connection between the cover and casing, a switch mechanism within the casing and means secured to the interior side wall of the casing cooperating with the switch mechanism to prevent removal of the cover while the switch is in closed relation to circuits connected thereto.

65 11. A switch comprising a casing, a removable cover, a switch mechanism within the casing and secured to and removable with the cover and rotatable therewith, a handle to move the switch mechanism to either its open or closed position and a spring connecting the handle and switch mechanism to transmit a yielding motion to the switch to cause a quick break opening of the switch and means to prevent removing the cover until the switch mechanism is in its fully open position and auxiliary concealed means on the cover and casing cooperating to prevent removal of the cover until the switch is open.

70 12. A switch comprising a casing, a removable cover interlocked by rotation with the casing, a switch mechanism within the casing and secured to and removable and replaceable with the cover, a rotatable shaft secured to the cover only to move the switch mechanism to either its open or closed position, the casing and cover forming a gas tight receptacle and the cover removable only by rotation about the axis of the shaft and means to prevent replacing the switch mechanism within the casing only with the switch mechanism in its fully open relation.

75 13. A switch comprising a casing and a removable cover screw-threaded to the casing, a switch mechanism within the casing and means on the casing cooperating with the switch mechanism to limit the rotation of the cover until the switch mechanism is in its open position.

80 14. A gas and flame proof switch comprising a casing, a removable cover secured thereto, a rotatable switch mechanism within the casing, means around the inner periphery of the casing to engage with the switch mechanism between the closed and fully open position of the switch to prevent removing the cover until the switch is fully open, temporary connections to the switch mechanism and means external of the casing to prevent making or removing the connections while the switch is closed.

85 15. A switch comprising a casing and a detachable cover secured thereto by interengaging means operated by relative rotation of the cover and casing, terminals secured to the casing to receive conductors exterior of the casing and forming an airtight connection therewith, a switch mechanism within the casing to connect certain of the terminals,

90 95 100 105 110 115 120 125 130

the switch comprising a plurality of connecting devices mounted on a rotatable insulated member and positioned in different parallel planes with their axes at right angles, means to secure the rotatable member to the cover, means to operate the rotatable member from without the casing and members of the switch mechanism arranged to engage means on the casing to prevent removal of the cover while the switch is in its closed position.

16. A switch comprising a metal casing and a detachable metal cover therefor, terminals, a switch mechanism located in the casing, a separately formed insulating lining to the inner surface of the casing provided with circumferential slots and slots transverse to said circumferential slots and the said slots coacting with the switch mechanism to prevent removal of the cover until the switch is fully open and preventing closing the switch until the cover is substantially replaced.

17. A switch mechanism comprising a casing and a cover removably secured together, two pair of terminals extending through the wall of the casing and each pair positioned in spaced parallel planes and parallel with the bottom of the casing, a rotatable insulating member mounted on a shaft secured to the cover and rotatable with the shaft about its axis at right angles to the planes of the terminals, connecting members mounted on each side of the insulating member and projecting therefrom in the planes of its terminals to connect the terminals of each pair when the switch is closed and prevent a movement of the insulating member, connecting members, and the shaft in a parallel direction of the axis of the shaft, means interlocking the cover with the shaft permitting relative rotation but not relative movement along the axis of the shaft and an interlock between the casing and cover to prevent removal of the cover while the switch is closed.

18. A switch comprising a casing and a rotatable cover removably secured together by a screw threaded connection therebetween, external means operable by a key to lock the casing and cover against rotation by unauthorized persons, insulated terminals secured to the casing, contact plugs to be connected to and disconnected from the terminals, a switch mechanism to connect the terminals and means to prevent the disconnecting of the plugs or removal of the cover by an authorized person while the switch is closed or replacement of the cover while the switch is in a position to connect the terminals.

19. A switch comprising a gas proof receptacle and a switch mechanism mounted therein, the receptacle comprising a casing and a removable cover, switch mechanism rotatably mounted on the cover within the receptacle and removable with the cover only

and connecting terminals projecting through the walls of the receptacle to connect to cables exterior of the receptacle, the switch mechanism interlocked with the terminals when closed and preventing removal of the cover, concealed interlocking means between the cover and casing and disengaged by rotation of the cover, when the switch mechanism is out of engagement with the terminals, means to prevent rotation of the cover to remove the same by an unauthorized person and means on the casing coacting with the switch mechanism to prevent removal or replacement of the cover and switch mechanism by an authorized or unauthorized person until the switch mechanism stands in an open relation to the terminals.

In testimony whereof I affix my signature.
HOMER P. CHANDLER.
